ATTORNEY

UNITED STATES PATENT OFFICE

RICHARD CARVEL, OF NEW YORK, N. Y.

BUILDING CONSTRUCTION

Application filed September 11, 1930. Serial No. 481,086.

This invention relates to building construction and has as an object the provision of methods of forming concrete wall sections having the exterior appearance of masonry, but at a cost considerably lower than the cost of masonry walls.

Other objects and advantages of the invention will appear hereinafter.

A preferred embodiment of the invention selected for purposes of illustration is shown in the accompanying drawings, in which,

Figure 1 is a section on the line 1—1 of Figure 2, showing the arrangement of the stone and the separating strips.

Figure 2 is a section on the line 2—2 of Figure 1.

Figure 3 illustrates the manner in which the mating sections of the finished wall fit together.

The invention to be described and claimed in this application relates generally to the type of building construction disclosed and described in my prior application Serial No. 225,426, filed October 11, 1927, in which it is proposed to cast wall sections of relatively large size, and then to set up the sections to form a finished wall, instead of building the wall piece by piece as is now common practice. It was also proposed to provide facing material for the said wall sections which would give the external appearance of ordinary masonry or brick walls.

According to the present invention, the same general procedure is followed to the extent that the wall sections are cast in a suitable form and are then set up to form a finished wall, but it is proposed to treat the wall section in such manner that adjoining units may be easily assembled in such manner that the appearance of ordinary masonry is obtained.

For this purpose, a box or form 1 is provided of any desired length, width and depth and a thin layer of sand 2 or other suitable material for protecting the front of the facing material is placed in the bottom of the said box. Immediately on top of the layer of sand and pressed therein to any desired depth is arranged a layer of stone or other suitable facing material 3, the individual

stones or units being placed in close proximity one to another. At intervals sufficient to provide wall sections of suitable size for convenient handling are placed separating strips 3 of rubber or other suitable flexible material, the said strips being preferably sufficiently flexible so that they may conform readily to the shape of the individual stones or units as illustrated in Figure 1. After the separating strips are thus placed in position, a layer of concrete is poured into the form on top of the layer 2, thus embedding the stones or units of the layer 2 therein, but leaving the bottom surfaces of the said stones or units clear, due to their protection by the layer of sand 1. As will be understood, the sand may be washed from the finished units after they have been removed from the form.

After the concrete is poured, it is permitted to set and harden, but after the concrete is set and before it has hardened completely, the separating strips 3 may be withdrawn thus leaving, in effect, a plurality of separate wall sections having mating irregularities in the adjoining faces.

As will be apparent, when it is desired to build the wall, the wall sections may be removed from the form, transported to the desired position, and the adjoining wall sections may be set up as illustrated in Figure 3, the sections being placed one on top of the other with a thin layer of grout between. When the wall is completed and the grout has dried, it is impossible to detect the line of separation between the sections, and to all external appearances the wall is a solid wall of masonry.

It is to be understood that the invention may be variously modified and embodied within the scope of the subjoined claims.

I claim as my invention:

1. The method of forming concrete wall sections which comprises laying protecting material in a form of predetermined size and shape, laying facing material thereon, separating certain portions of the facing material along an irregular line by placing a spacing member therebetween conforming to the shape of said facing material, and pouring concrete over the facing material to bind the

same together except along the line of separation.

2. The method of forming concrete wall sections which comprises laying protecting material in a form of predetermined size and shape, laying facing material thereon, separating certain portions of the facing material by placing a flexible spacing member therebetween which conforms to the shape 10 of the facing material, and pouring concrete over the facing material to bind the same together except along the line of separation.

3. The method of forming concrete wall sections which comprises laying protecting material in a form of predetermined size and shape, laying facing material thereon, separating certain portions of the facing material along an irregular line by placing a spacing member therebetween conforming to the 20 shape of said facing material, pouring concrete over the facing material to bind the same together except along the line of separation, removing the spacing material, disassembling the sections, and reassembling 25 and binding the sections in the same relationship with grout.

4. The method of forming concrete wall sections which comprises laying protecting material in a form of predetermined size and shape, laying facing material thereon, separating certain portions of the facing material by placing a flexible spacing member therebetween which conforms to the shape of the facing material, pouring concrete over the 35 facing material to bind the same together except along the line of separation, removing the spacing material, disassembling the sections, and reassembling and binding the sections in the same relationship with grout.

40 5. The method of forming concrete wall sections which comprises laying facing material in a form of predetermined size and shape, placing a flexible spacing member therebetween which conforms to the shape of 45 the facing material, and pouring concrete over the facing material to bind the same together except along the line of separation.

6. The method of forming concrete wall sections which comprises laying facing material in a form of predetermined size and shape, placing a flexible spacing member therebetween which conforms to the shape of the facing material, pouring concrete over the facing material to bind the same together 50 except along the line of separation, removing the spacing material, disassembling the sections, and reassembling and binding the sections in the same relationship with grout.

60 In testimony whereof, I have signed my name to this specification this fifth day of September, 1980.

RICHARD CARVEL.
